COMBINED WRITING PAD AND PENCIL HOLDER

Richard J. McFadyen, Upper Montclair, N. J., assignor to Ketcham and McDougall, Inc., Roseland, N. J., a corporation of New Jersey

Application November 10, 1954, Serial No. 33,057

Term of patent 14 years

(Cl. D74—1)

Fig. 1.

Fig. 2.

Fig. 3.

Fig. 1 is an isometric view of a combined writing pad and pencil holder showing my new design;

Fig. 2 is an isometric view thereof taken from the opposite side; and

Fig. 3 is a side elevational view thereof as it appears with the pencil raised to writing position.

I claim:

The ornamental design for a combined writing pad and pencil holder, substantially as shown.
